INVENTOR:
IRVING H. VANHORN,
BY Alfred S. Hunt
His ATTORNEY.

UNITED STATES PATENT OFFICE.

IRVING H. VAN HORN, OF EAST CLEVELAND, OHIO, ASSIGNOR TO GENERAL ELECTRIC COMPANY, A CORPORATION OF NEW YORK.

BASE FOR INCANDESCENT LAMPS OR SIMILAR ARTICLES.

Application filed September 20, 1926: Serial No. 136,405.

My invention relates to bases for electric incandescent lamps and similar devices. In high wattage lamps, particularly of the gas-filled type disclosed in United States Patent 5 1,180,159, convection currents cause the heat to be transferred rapidly from the filament to the base of the lamp. In lamps of the higher wattage gas-filled type, considerable difficulty has been experienced in obtaining 10 a basing cement which would stand this heat and securely hold the base to the lamp after it had been in operation a short while.

According to my invention, I overcome this difficulty by providing a clamping means in 15 the form of an auxiliary portion which may be attached to an ordinary lamp base or may form part of the base itself, and when properly placed on an incandescent lamp bulb will securely hold the base thereto under all 20 temperature conditions. My invention also has the advantage that the basing cement may be entirely dispensed with, thereby causing a saving in the manufacture of these lamps. Other features and advantages will appear 25 from the following description taken in connection with the accompanying drawings, in which:

Fig. 1 is an elevation of a species of a clamp and base constructed in accordance with my 30 invention; Fig. 2 is a sectional plan along the line 2--2 of Fig. 1; Fig. 3 is an elevation of a gas-filled electric incandescent lamp having my invention applied thereto; and Fig. 4 is an enlarged section along the line 35 4--4 of Fig. 3.

Referring to the drawing, and particularly Fig. 3, 10 is a bulb of an electric incandescent lamp having a stem 11. The leading-in conductors 12 and 13 have their ends sealed into 40 the flattened portion 14 of the stem and are electrically connected to the metal supports 15 and 16 respectively, the ends of which are also embedded in the flattened portion 14. The said conductor supports 15 and 16 are 45 electrically connected at their other ends to a filament 17, which, as shown, is of the concentrated coiled type. The flattened portion 14 of the stem 11 has extending therefrom a glass arbor 18 which extends into an arbor 50 tube 19, said tube being supported by the horizontally disposed wires 20--21 attached to the conductor supports 15 and 16 respectively. The above described construction is 55 of the same general type as that disclosed in my prior application, Serial No. 113,315,

filed June 22, 1926, for electric incandescent lamps. A plurality of wire hooks or supports 22 carried by the arbor tube 19 engage the filament 17 and serve to support and maintain it in the desired shape. 60

The lamp bulb 10 comprises a suitable neck 23, the end of which receives the skirted portion 24 of an ordinary lamp base 25. A quantity of cement 26 applied to the interior of the skirted portion serves to hold the base and bulb together in most cases, but with lamps of especially high wattage, the temperature is great and the baffle or disc, such as 27 shown in Fig. 3, will not always serve to prevent the heat from injuriously affecting the cement and causing the base to become loosened from the bulb neck. This difficulty is overcome by a clamp which may be integral with the base or may be attached to the skirted portion thereof. As shown in 70 the drawing, the clamp consists of a metal stamping (preferably brass) in the form of a split ring or sleeve 28 having a plurality of fingers 29 which are attached to the skirted portion 24 of the base. The sleeve 28 may 75 be lined with a thin strip of heat insulating material 30, such as asbestos, which also has a gripping and cushioning effect. In assembling, the base is applied to the end of the bulb neck in the usual manner, after which 80 the sleeve 28 is clamped around the neck of the bulb. This is accomplished by a gripping tool, such as a pair of ordinary pliers, which are caused to take hold of the grips 31 and 32 and draw the ends of the split ring together. 85 After the ring has been properly tightened, a tab 33 which extends through a slot 34 of the sleeve is bent back upon itself as shown in Fig. 2, so as to securely clamp and lock it. In order to insure the security of the sleeve, 90 about the neck of the bulb, an adhesive such as sodium silicate may be applied to the insulating material 30. 95

What I claim as new and desire to secure by Letters Patent of the United States is: 100

1. The combination of an electric incandescent lamp comprising a neck and a bowl portion and a base having the usual portion carrying the electrical terminals and engaging the end of said neck and a gripping extension 105 comprising a split ring integral with said extension engaging an intermediate portion of said neck, and means for holding the adjacent ends of said ring together to cause said ring to grip said neck. 110

2. The combination of an electric incandescent lamp comprising a neck and a bowl portion and a base having the usual portion carrying the electrical terminals and engaging the end of said neck and a gripping extension comprising a split ring integral with said extension engaging an intermediate portion of said neck, and means whereby the adjacent ends of said ring may be drawn together and locked to cause said ring to grip said neck.

3. The combination of an electric incandescent lamp comprising a neck and a bowl portion and a base having the usual portion carrying electrical terminals and engaging the end of said neck, a split ring engaging an intermediate portion of said neck and a plurality of fingers depending from the lower portion of said base and integral with and supporting said ring, and means for holding the adjacent ends of said ring together to cause said ring to grip said neck.

4. The combination of an electric incandescent lamp comprising a neck and a bowl

portion and a base having the usual portion carrying the electrical terminals and engaging the end of said neck, a split ring engaging an intermediate portion of said neck and a plurality of fingers depending from the lower portion of said base and integral with and supporting said ring, heat insulating means interposed between said ring and said neck, and means for holding the adjacent ends of said ring together to cause said ring to grip said neck.

5. The combination of an electric incandescent lamp comprising a neck and a bowl portion and a base having the usual portion carrying the electrical terminals and engaging the end of said neck and a gripping extension comprising a split ring integral with said extension engaging an intermediate portion of said neck, and means formed integral with said ring for locking its adjacent ends together to grip said neck.

In witness whereof, I have hereunto set my hand this 17th day of September, 1926.

IRVING H. VAN HORN.
